SEWING MACHINE

George Sauer, Berwyn, Ill., assignor to Union
Special Machine Company, Chicago, Ill., a cor-
poration of Illinois

Application August 1, 1938, Serial No. 222,398

11 Claims. (Cl. 184—6)

This invention relates to sewing machines, and is concerned more particularly with lubrication of the moving parts of such machines.

Amongst the objects of my invention are to provide for automatic delivery of oil to the moving parts of the stitch forming, feeding and driving mechanisms of sewing machines by controlled flow, and to provide for maintenance of the flow automatically without restricting the speed of the sewing machines or impairing their operative efficiency.

One way in which the foregoing and other advantages may be readily realized in practice will be understood from the following detailed description of the attached drawings, wherein Fig. I is a view in longitudinal section of a sewing machine suitably embodying my invention.

Fig. II is a horizontal sectional view of the machine taken as indicated by the arrows II—II in Fig. I.

Figs. III and IV are cross-sections taken as respectively indicated by the arrows III—III and IV—IV in Figs. I and II.

The sewing machine chosen for convenience of illustrating my invention is of the flat bed type having a skeletonized open frame base 1 with an integrally formed hollow standard 2 rising therefrom at one end thereof and supporting an overhanging arm 3 which terminates in a guide head 4 for needle and presser bars 5 and 6. In accordance with my invention the base is provided with top, side and end walls 7, 8, 9, 10 and 11, and with partitions 12, 13, 14 which set apart chambers 16, 17 and 18 respectively for the accommodation of complementary stitch forming and feeding mechanisms 19 and 20, devices 21 by which the threads used in the sewing are tensioned, and a portion of the driving mechanism 22. As shown, the base 1 has an opening in its top 7 closed by a removable inset plate 23 which, in conjunction with said top, constitutes the work support, and at the bottom by a removable plate 24, which (Fig. I) for drainage purposes, slopes downward from the left-hand end of the machine to an oil sump S at the rear end of said base.

The complementary stitch forming mechanism 20 of the machine includes a pair of four motion loopers 25 supported in a common holder 27 which is pivoted on a stud 28 projecting laterally from a sleeve 29 fast on a rock shaft 30. As shown, the opposite ends of the rock shaft are journaled respectively in bearings 31 and 32 afforded by the left-hand end wall 8 of the base and the cross partition 12. The rock shaft 30 is oscillated through the medium of a link 33 by an 55

eccentric 35 on a shaft 36 extending longitudinally through the base 1. As shown, the shaft 36 is journaled adjacent its front end in a bearing sleeve 37 set into the left-hand end wall 8 of the base 1, and adjacent its rear end in a bearing 38 depending from the top wall 7. At a medial point, the shaft 36 is rotatively supported in a bearing 39 afforded by the partition 12. By means of an upwardly-collapsible link 40, the looper holder 27 is coupled with an upright arm 41 on a transverse rock shaft 42 whereof the opposite ends are journaled in the sides of a recess 43 in the transverse partition 12 through which recess the sewing threads pass enroute from the tensioning devices 21 to the loopers 25. To the inner end of the rock shaft 42, beyond the partition 12, is affixed a horizontal arm 45 which extends rearward beneath the bottom 46 of the compartment 17 and which, by means of a vertical link 47, is coupled with a crank 48 on the shaft 36 as shown in Fig. I. By the parts just described, the loopers 25 are caused to cooperate with a pair of needles of which one is shown at 49 in Fig. I carried by the needle bar 5 in a well known way to form seam stitches.

The feeding mechanism 19 of the machine comprises a four motion feed dog (not shown) which is adapted to react upwardly upon a presser foot 50 at the lower end of the presser bar 6. A horizontal bar for supporting the feed dog is shown at 51. At its rear end the feed bar 51 carries a pin 52 having its ends engaged in pivot bearings 53 at the top of a vertical rocker arm 55. The rocker arm 55 is in turn affixed to a rock shaft 56 at the back of the machine, said rock shaft extending parallel with the shaft 36 and being journaled in bearing bushings 57, 58 set respectively into the end wall 8 of the base and into a post 59 within said base. A horizontal arm 60 at the outer end of the rock shaft 56 is connected by a vertical link 61 with an eccentric actuator 62 at the protruding left hand end of the shaft 36. The elements just described serve to impart horizontal feed movements to the feed dog to progress the material (not shown) being sewed in the machine, crosswise of the top of the base 1 which constitutes the work support. Another rotary actuator shown at 65 in Fig. II and suitably connected to the feed bar 51 serves to induce the necessary lift movements in the feed dog. The illustrated feeding mechanism is generally like that featured in U. S. Patent No. 2,048,874 granted to F. A. Kucera on July 28, 1936, to which reference may be had for details if found necessary.

The needle bar 5 of the machine is operated, through suitable connections (not illustrated), from a drive shaft 66 which extends longitudinally through the hollow of the overhanging arm 3. As shown in Fig. I, the drive shaft 66 is journaled in spaced bearings 67, 68 provided by an upward continuation 69 of the left hand end wall of the standard and by the right hand end wall of said standard, and at its protruding end carries a combined hand and belt wheel 70 so that the machine may be operated either manually or under power. By means of a transmission gear train including spur pinions 71, 72 and an intermediate intermeshing idler spur wheel 73, rotary motion is transmitted at like speed from the upper or drive shaft to the lower shaft 36. As shown the intermediate gear 73 is fast on a horizontal counter shaft 74 journaled at opposite ends in another pair of bearings 75, 76 respectively on the opposite walls of the standard 2.

For the purposes of automatic lubrication in a sewing machine such as described up to this point, I have made provisions as follows: Mounted on the lower rotary shaft 36 at opposite sides of the spur pinion 72 but spaced somewhat from the latter are disks 77, 78 which dip into oil maintained at the level L in the sump S of the base 1. By the rapid rotation of these disks 77, 78, oil is thrown upwardly within the hollow of the standard 2. Due to the rapid rotation of the disks 78 the oil so lifted takes the form of a heavy mist, which, through constant systematic agitation of the air within the hollow of the standard by the fast revolving gears 71—73 of the transmission train is dispersed in all directions and precipitated upon the parts and surfaces within said chamber. It is to be observed in this connection that the lower pinion 72 of the gear train within the column 2 is so proportioned as shown in Fig. I that it does not at any time dip into the lubricant. In this way, churning and deterioration of the oil is effectively precluded. Some of the oil dispersed as above explained finds its way into the bearings 67, 68 of the upper or drive shaft 66 through holes 67a, 68a leading down into said bearings from the top, and some of it into the bearings 75, 76 of the counter-shaft 74 similarly by way of holes 75a, 76a in the latter bearings, while some of it is caught in a small reservoir 79 formed in an inward prolongation of the top wall 7 of the base 1 within the hollow of the standard 2. Some of the oil, moreover, impinges upon the gears 71—73 to keep them well bathed. The bearing 38 for the lower shaft 36 also receives its share of the oil. Through provision of the disks 78 at opposite sides of the pinion 72 and lateral spacing of said disks from said pinion to avoid contact with the intermediate gear 73, the oil is elevated at both sides of the gear train for more effective distribution of the mist within the standard. Leading down at an inclination from the reservoir 79 (Fig. I) through an inwardly projecting rib 80 (Fig. III) on the rear side wall 11 of the base 1 is a duct 81 which meets a longitudinal distributing channel 82 in the lower edge of said wall closed by the bottom plate 24. As shown in Figs. I and II, the distributing channel 82 extends from the point of its juncture with the inclined duct 81 to the left hand end of the base 1 where a transversely-extending horizontal duct 83 meets with it. Connecting into the front end of the duct 83 (Figs. I and II) is an upwardly reaching tube 84 which terminates above the

link 61 associated with the eccentric actuator 62 on the shaft 36 by which feeding movements are imparted to the feed bar 51. Into the end of the tube 84 is stuffed a wick 85 which wipes 5 against the top of the link 61. Also leading from the horizontal duct 83 are branch ducts 86, 87 which extend respectively to the bearings 31 and 37 for the shafts 30 and 36, see Figs. I and II. Rising from the distributing channel 82 at the 10 rear side of the machine base 1, respectively in the left hand end wall 8 and the column 59, are ducts 88, 89 with connecting tubes 90, 91 which extend over the top of the pivot bearings 53 of the feed rocker 55 and which terminate in wiper wicks 92 and 93, see Fig. II. At the rear of the 15 machine base 1 within the partition 12 is a duct 94 which extends up from the distributing channel 82 to a transverse duct 95 which carries oil to the medial bearing 39 for the shaft 36 and 20 also to the bearing 32 for the looper rock shaft 30. Connecting laterally into the duct 95 are wick tubes 96, 97 which terminate above the 25 rotary actuators respectively embodied in the feeding and complementary stitch-forming mechanism 19, 20. From the front end of the duct 95 leads a wick tube 98 which terminates above the pivot connection between the link 40 and arm 41 of the complementary stitch-forming mechanism 20. Another duct 99 leading upward from 30 the distributing channel 82 within the rear side wall of the base 1 connects with a transverse duct 100 in the top wall 7 of the base and carries oil to a wick-stuffed aperture 101 directly above the link 47 connecting a crank 48 on the shaft 36 35 with the arm 45 on the rock shaft 42. It is to be particularly noted from Fig. I that the reservoir 79 is above the level of the several transverse ducts 83, 95 and 100 so that just sufficient head pressure is maintained upon the oil in the distributing channel 82 to cause slow upward flow of the oil in the vertical ducts for apportionment of the oil and effective lubrication of the parts of the machine mechanism. The compartment 16 containing the feeding and complementary 40 stitch-forming mechanisms 19 and 20 is closed at the bottom by a horizontal diaphragm 102 which extends between the end wall 8 and the partition 12 as shown in Fig. I. Set upwardly into an opening 103 in the diaphragm is a removable plate 104 which in turn has a central opening with an insert screen 105. Clamped against the bottom of the plate 104 by a centrally open holder plate 106 is a web 107 of filtering material held between screens 108, 109, see Figs. I and IV. The oil released from the parts within the chamber 16 and collected in the bottom of the latter 45 seeps downward through the screening and filtering material back into the oil supply in the bottom of the base 1. Lint or other solid matter carried along with the oil in its circulation through the machine is thus removed, and the oil filtered before it is returned to the main supply in the base 1 for re-circulation. 50

The bearing 38 is lubricated by oil fed through a duct 38a from the reservoir 79.

From the foregoing, it will be seen that I have provided a simple automatic circulating lubricating system which, under definite control, supplies an ample amount of lubricating oil to the moving parts of the machine without unnecessary excess flow and does not require the expenditure of power for its actuation and therefore does not impair efficiency of the sewing machine.

Having thus described my invention, I claim:

1. In a sewing machine, a base with a work support having an integrally formed pendant web of uniform depth to define a continuous chamber wall, a channel in the bottom edge of said web, and a removable cover plate secured fluid tight against the bottom edge of the wall for capacity to retain a supply of lubricating oil in the chamber, said plate also closing the channel; looper and feeding mechanisms within the chamber; and means whereby oil is conducted from the supply within the chamber by way of the channel aforesaid to various parts of the stitch forming and feeding mechanisms.

2. A sewing machine according to claim 1, in which there is an auxiliary gravity feed oil reservoir at an elevation within the chamber; means for lifting oil from the supply to said reservoir; and a duct leading down from the reservoir to the channel.

3. A sewing machine according to claim 1, in which there is an auxiliary gravity feed oil reservoir at an elevation within the chamber; means for lifting oil from the supply to said reservoir; a duct leading down from the reservoir to the channel; and means within the base for filtering the excess oil released from the looper and feeding mechanisms before it is returned to the main supply for redistribution.

4. In a sewing machine, a base with a work support having a pair of integrally-formed laterally spaced interconnecting pendant longitudinal and plural spaced crosswise webs whereof the bottom edges all meet in a common horizontal plane, an auxiliary gravity feed oil reservoir at an elevation interiorly of the base, an oil distributing channel extending lengthwise of the bottom of one of the longitudinal webs, an oil flow passage leading down from the auxiliary reservoir through one of the cross webs to the channel, ducts leading upward from the channel through others of the cross webs, and a removable plate secured fluid-tight against the bottom edges of the longitudinal and endmost cross webs to form a closed housing capable of holding a supply of lubricating oil, said plate also closing the bottom of the oil distributing channel; means for lifting oil from the supply in the housing to the auxiliary reservoir; looper and feed mechanisms within the housing; and means for conducting oil from the several ducts to the various moving parts of said mechanisms.

5. A sewing machine according to claim 4, including means within the housing for filtering the excess oil released from the looper and feeding mechanisms before it is returned to the main supply in the bottom of the housing for redistribution.

6. A sewing machine according to claim 4, including a shaft from which the looper and feed mechanisms are actuated, extending lengthwise through the base housing and journaled in certain of the cross webs; bearings for the shaft and means whereby oil is conducted to said bearings from certain of the vertical ducts.

7. A sewing machine according to claim 4, in which a hollow intercommunicating standard rises from the base housing at one end of the latter and sustains above the work support, an overhanging needle arm; wherein the auxiliary reservoir is within the hollow of the standard; wherein a rotary shaft, from which the looper and feed mechanisms are actuated, extends lengthwise through the base housing; wherein a needle mechanism is actuated from a main drive shaft which extends lengthwise through the over-

10 hanging arm and is journaled in opposite sides of the standard; wherein the looper and feed actuating shaft is connected to the main shaft by gearing within the standard; and wherein the oil elevating means takes oil from the supply in the base housing and disperses it upwardly within the standard so that some of it reaches the gearing and the journals for the main shaft, and some of it is caught in the auxiliary reservoir.

8. A sewing machine according to claim 4, in which a hollow intercommunicating standard rises from the base housing at one end of the latter and sustains above the work support, an overhanging needle arm; wherein the auxiliary reservoir is within the hollow of the standard; wherein a rotary shaft, from which the looper and feed mechanisms are actuated, extends lengthwise through the base housing; wherein a needle mechanism is actuated from a main drive shaft which extends lengthwise through the arm and is journaled in opposite side walls of the standard; wherein the looper and feed actuating shaft is connected to the main shaft by gearing within the standard; and wherein the oil elevating means includes a disk on the looper and feed shaft which dip into the oil supply in the base housing and disperses it upwardly within the standard so that some of it reaches the gearing and the journals for the main shaft, and some of it is caught in the auxiliary reservoir.

9. A sewing machine according to claim 4, in which a hollow intercommunicating standard rises from the base housing at one end of the latter and sustains above the work support, an overhanging needle arm; wherein the auxiliary reservoir is within the hollow of the standard; wherein a rotary shaft, from which the looper and feed mechanisms are actuated, extends lengthwise through the base housing; wherein a needle mechanism is actuated from a main drive shaft which extends lengthwise through the arm and is journaled in opposite side walls of the standard; wherein the looper and feed actuating shaft is connected to the main shaft by a train of spur gears within the standard; and wherein the oil elevating means comprises a pair of disks on the looper and feed shaft respectively on opposite sides of the lowermost gear of the train, which disks dip into the oil supply in the base housing and disperse it upwardly within the standard so that some of it reaches the upper gears and the journals for the main shaft, and some of it is caught by the reservoir.

10. A sewing machine according to claim 4, in which an integral horizontal partition above the bottom closure plate, forms in conjunction with the longitudinal webs and certain of the cross webs, a lubrication chamber for the looper and feed mechanisms and a separate compartment for the oil supply and the auxiliary reservoir; and wherein a screen retractable from an opening in said partition after removal of the bottom plate filters the excess oil released from said mechanisms before it is returned to the oil supply compartment; and wherein the aforesaid chamber is provided with a removable cover recessed in the work support for convenience of access to the looper and feed mechanisms.

11. A sewing machine according to claim 4, in which an integral horizontal partition above the bottom closure plate, forms in conjunction with the longitudinal webs and certain of the cross webs, a lubrication chamber for the looper and feed mechanisms and a separate compartment

for the oil supply and the auxiliary reservoir; and wherein a screen removable from an opening in said partition after removal of the bottom plate, filters the excess oil released from said mechanisms before it is returned to the supply in the oil compartment; wherein the said chamber is provided with a removable cover recessed in the work support for convenience of access to

the looper and feed mechanisms; and wherein the said chamber has a laterally offset portion for the shielding of a looper thread tension means against contamination by oil, which offset portion extends part way over the aforesaid compartment and is also accessible upon removal of the cover.

5
GEORGE SAUER.
